UNITED STATES PATENT OFFICE.

MEREDITH LEITCH, OF POUGHKEEPSIE, NEW YORK, ASSIGNOR TO THE DE LAVAL SEPARATOR COMPANY, OF NEW YORK, N. Y., A CORPORATION OF NEW JERSEY.

OPENING MEANS FOR CENTRIFUGAL BOWLS.

1,343,325.

Specification of Letters Patent. Patented June 15, 1920.

Application filed February 14, 1919. Serial No. 276,886.

To all whom it may concern:

Be it known that I, MEREDITH LEITCH, a citizen of the United States, residing at Poughkeepsie, county of Dutchess, and 5 State of New York, have invented a new and useful Improvement in Opening Means for Centrifugal Bowls, of which the following is a full, clear, and exact description, reference being had to the accompanying 10 drawings, which form a part of this specification.

My invention relates to means for unscrewing, from a centrifugal bowl, the nut that holds the parts thereof in an assembled relation. The object of my invention 15 is to provide means attached to the centrifugal machine frame for easily removing the bowl nut.

Many centrifugal bowls have a large bottom, from the center of which rises a hollow stem, screw-threaded on the outside of its upper end. A bowl shell, with its lower edge fitting against the large bottom, surrounds this stem and is held in place by a 25 nut screwed thereon. Ordinarily, when it is desired to clean such a bowl, it is removed from the machine, carried to a more or less distant place and secured in a special clamping ring. A special wrench or spanner is 30 then applied to the nut to remove it from the bowl. The clamping ring must be released before the bowl can be taken away for washing. When assembling the machine, this process must be reversed.

35 The object of my invention is to provide means on the frame of the machine for removing the nut without recourse to independent clamps, wrenches, etc.

In the accompanying drawings, which 40 illustrate several embodiments of my invention:—

Figure 1 shows a separator bowl in section with the disks omitted.

Fig. 2 shows a separator frame provided 45 with my invention, the bowl being shown in full lines in its normal working position and in dotted lines in position for removing the nut.

Fig. 3 is a front view of a portion of the 50 frame showing one form of my invention.

Fig. 4 is a horizontal cross-section through same.

Figs. 5 and 6 are views, corresponding to

Figs. 3 and 4, of another form of my invention.

55

Fig. 7 is a view, similar to Fig. 3, of another form of my invention.

Fig. 8 is a vertical cross-section through same.

Figs. 9 and 10 are views, corresponding to 60 Figs. 7 and 8, of another form of my invention.

a represents the frame or stand for supporting the driving mechanism and the frame *b*, which in turn supports the bowl. 65 *c* is the bowl bottom, *d* the hollow stem, *e* the bowl shell and *f* the nut threaded on the end of stem *d* and holding in place the bowl shell *e*.

In Figs. 3 and 4, the frame *b* carries two 70 pins *g*, *g* and a guide pin *h* slightly smaller than the hole in the top of the bowl and located centrally between the two pins *g*, *g*.

In Figs. 5 and 6, the frame carries two 75 pins *i*, *i*, similar to pins *g*, *g*, and is provided with a socket *j* of a diameter slightly greater than the bowl nut.

In Figs. 7 and 8, the frame has a guide pin *k* similar to and functioning like pin *h*. *m* is a pin secured in a lug *n* projecting toward the center of the guide pin *h*.

In Figs. 9 and 10, the frame has a pin *o*, 80 similar to pin *m*, projecting radially inward from the periphery of a socket *p*, similar to socket *j*.

The nut of a centrifugal bowl is ordinarily provided either with two holes in its top adapted to receive two pins in a wrench, or with radial holes in its circumference adapted to receive a pin in a spanner. The 90 two pins *g*, *g* of Figs. 3 and 4, or the two pins *i*, *i* of Figs. 5 and 6, are of a size and a center distance adapted to enter the above mentioned holes in the top of the nut. The single pin *m* shown in Figs. 7 and 8, or the 95 single pin *o* shown in Figs. 9 and 10, is adapted to enter a spanner hole in the circumference of the nut.

When it is desired to disassemble a centrifugal bowl, the operator presents the nut 100 to the frame, where, guided by the guide pin *h* or *k*, or by the socket *j* or *p*, it is easy to engage the top holes in the nut with the pins *g*, *g* or *i*, *i*, or one of the radial holes in the nut with the pin *m* or pin *o*. With both 105 hands on the large diameter lower portion

of the bowl, the operator can turn it to loosen the nut. The bowl may then be carried to any convenient place for washing. After the bowl is washed and assembled, the nut may be tightened in the same manner.

Having now fully described my invention, what I claim and desire to protect by Letters Patent is:

1. Means for unscrewing centrifugal bowls from their holding nuts comprising a fixedly positioned frame, means thereon engageable with the nut to prevent its rotation, and guiding means on the frame to guide the bowl nut into engagement with the rotation preventing means.

2. Means for unscrewing centrifugal bowls from their holding nuts comprising a fixedly positioned frame, and means thereon adapted to engage the holding nut, when the bowl is brought to a position wherein its axis extends horizontally and is thrust laterally against the frame, and hold said nut stationary while the bowl is turned to loosen the nut.

3. Means for unscrewing centrifugal bowls from holding nuts having two wrench-

engageable holes comprising a fixedly positioned frame, two pins thereon adapted to be engaged with said holes, and guiding means on the frame to guide the nut into engagement with said pins.

4. Means for unscrewing a centrifugal bowl having a top hole from a holding nut having a wrench-engaging hole, comprising a fixedly positioned frame, a pin on the frame, and a guide pin on the frame adapted to engage the top hole of the bowl and guide the hole of the nut into engagement with the pin on the frame.

5. Means for unscrewing centrifugal bowls having a top hole from holding nuts having two wrench-engageable holes, comprising a fixedly positioned frame, a guide pin thereon slightly smaller than the inside of the top hole of the bowl, and two adjacent pins adapted to enter the holes in the bowl nut and prevent rotation of the nut when the bowl is turned.

In testimony of which invention, I have hereunto set my hand, at Poughkeepsie, N. Y., on this 11th day of February, 1919.

MEREDITH LEITCH.
